UNITED STATES PATENT OFFICE.

JOSEPH H. ROBBINS, OF OWOSSO, MICHIGAN.

EXTENSION-TABLE.

SPECIFICATION forming part of Letters Patent No. 556,645, dated March 17, 1896.

Application filed August 27, 1895. Serial No. 560,694. (No model.)

To all whom it may concern:

Be it known that I, JOSEPH H. ROBBINS, a citizen of the United States, residing at the city of Owosso, in the county of Shiawassee 5 and State of Michigan, have invented certain new and useful Improvements in Extension-Tables, of which the following is a specification.

This invention relates to new and useful 10 improvements in extension-tables; and the invention consists in the peculiar construction of the device whereby the leaves of the extension-table are stored when not in use within the case or frame of the table and are 15 supported by the extension-slides in position, from whence they can be readily removed for use, the object of the invention being to form a convenient receptacle for the storing of the leaves when such leaves are not in use, and 20 also means for closing and concealing said receptacle by means of a hinged door or lid. These objects I accomplish by means of the mechanism illustrated in the accompanying drawings, in which—

25 Figure 1 shows an inverted plan of a table constructed in accordance with my invention, showing the position of the receptacles for the leaves and the hinges which attach the door or lid for concealing the leaves. Fig. 2 shows 30 an inverted end view of a table constructed in accordance with my invention with the lid opened and two of the leaves removed from one of the receptacles; and Fig. 3 shows a plan view of one of the leaves, showing my 35 preferred form of constructing the same.

Similar letters refer to similar parts throughout the several views.

A represents the rim or rail of a table constructed in any ordinary manner.

40 A' represents the stationary part of the table cover or top, it being understood that in the ordinary extension-table there is a leaf or cover which is stationary at each end of the table.

45 B represents the table-legs.

D D represent the outer slides or extension-bars, which are securely attached to one end of the table and are provided with grooves in the ordinary manner.

50 F F represent extension-bars secured to the other end of the table, and E E represent intermediate extension-bars. The number of

these extension-bars may be increased or decreased at pleasure; but I have shown the ordinary number used in an extension-table. 55

H is an intermediate grooved strip placed between the stationary extension-bars F F and serves to support one side or edge of the leaves when stored in their receptacles.

C C show the leaves in the receptacle.

M shows a cross-piece adapted to support the hinged door K.

Referring now to Fig. 2, where the ends of the leaves are shown in one of the receptacles, P P represent grooves, there being shown in 65 the drawings three grooves on each side of the center supporting-piece H and three grooves on each side of the extension-bars F F. The leaf shown by C in Fig. 3 is provided with studs or pins on each side, said pins adapted to attach the leaves together when in place upon the table, and also serving as supports for the leaves within the receptacles, the said studs or pins engaging with the grooves P P. By this construction the supports for the leaves require only very narrow grooves, which do not greatly weaken the slides and supports, and which retain the leaves securely in position, so that they will not come in contact to mar or injure their surfaces. 75

In the example of my invention shown in the drawings the receptacles are adapted to hold three leaves each; but it will be understood that these receptacles may be made so as to hold more or less; or in case of a table 85 where but few loose leaves are used a single receptacle may be substituted in place of the double receptacle shown in Fig. 2.

By my construction I utilize the extension bars or slides which are attached to one end 90 of the table as supports for the leaves when in place. I am enabled also to store the leaves at one end of the table and to conceal them entirely from sight and to use a full-length leaf, so that the table is symmetrical 95 when the leaves are inserted, and it is not necessary to use a hinged leaf, as has been done in some cases.

Having thus described my invention, what I claim to have invented, and desire to secure 100 by Letters Patent, is—

In an extension-table, the combination with the table-frame, of two extension-slides D, D, made rigid with one end of said frame,

the extension-slides F, F, made rigid with the other end of said frame and provided upon their adjacent faces with narrow grooves, a central support H arranged midway between 5 said extension-slides and provided upon each side with grooves coincident with the grooves in the extension-slides, the spaces between the central support and the extension-slides being each greater than the width of the table- 10 leaves and the spaces between the grooves being greater than the thickness of said leaves, table-leaves provided on their opposite edges with tenons adapted to engage the

grooves in the central support and extension-slides, whereby said leaves are supported out of contact with one another entirely by their tenons when stored within the table, and a hinged door adapted to conceal said lids, substantially as described.

In witness whereof I have hereunto set my 20 hand and seal in the presence of two witnesses.

JOSEPH H. ROBBINS. [L. S.]
